UNITED STATES PATENT OFFICE.

JAMES HEGGIE, OF CLYDEBANK, SCOTLAND, ASSIGNOR TO THE SINGER MANUFACTURING COMPANY, A CORPORATION OF NEW JERSEY.

SEWING-MACHINE.

1,263,239.

Specification of Letters Patent.

Patented Apr. 16, 1918.

Application filed April 13, 1915. Serial No. 21,175.

To all whom it may concern:

Be it known that I, JAMES HEGGIE, a subject of the King of the United Kingdom of Great Britain and Ireland, and residing at 5 Clydebank, Dumbartonshire, Scotland, have invented a certain new and useful Improvement in Sewing-Machines, of which the following is a specification.

This invention relates to improvements in 10 sewing machines, particularly glove sewing machines of the type fitted with an upright post for receiving the looper spindle, for uniting by means of a piqué seam the overlapping edges of the body and the fourchettes, etc., and has for its primary object to provide a machine of this class which offers greater convenience in use and in which the stitch-forming operation is effected silently, with greater precision and at 20 higher speed than heretofore.

In the accompanying drawings Figure 1 is 25 an end elevation of a sewing machine embodying the invention, the base of the machine frame being shown in section; Figs. 1^a and 1^b show details; Fig. 2 is an inverted plan of the machine base.

Referring to the drawings, a machine embodying the invention comprises a frame 1 hinged at 2 to one edge of a tray-like base 30 3, said base 3 being formed integral with a receptacle 4 projecting from its forward edge adjacent to the stitch-forming mechanism, and adapted to receive a spool 5. The 35 said receptacle 4 is formed with a hinged lid 6 having a depending bracket 7 supporting a horizontal pin 8 on which the spool 5 is mounted.

Mounted in the overhanging arm of the machine frame 1 is the main driving shaft 40 9 carrying at its rearward end the usual band wheel 10 and serving to transmit through suitable connections vertical reciprocating movements to the needle bar 11 and lifting and feeding movements to the presser bar 12.

In the upright member 13 of the bracket arm is housed a vertical shaft 14 which receives rotary movements from the main driving shaft 9 and carries at its lower end 50 a crank disk 15 fitted with a crank pin 16 to which is connected one end of a pitman 17 the other end of which is connected to a swinging looper driving arm 18 pivotally supported from the machine base and 55 formed with a cam slot 19 entered by a cam

follower (roller 20) carried by a crank 21 on the looper spindle 22, so that on rotation of the main shaft 9 oscillatory movements are imparted to the looper. The pitman 17 comprises a rod 17' whose opposite ends are 60 threaded into the terminal pieces 17'' and held against turning relatively to said terminal pieces by suitable lock-nuts 17'''.

As will be seen from the drawing, the cam-slot 19 is of curved form and is preferably convexed toward, although not necessarily directly toward, the pivot of the arm 18. As the arm 18 is vibrated to-and-fro, substantially the central portion of cam-slot 19 crosses the axis of the looper-spindle 22 70 carrying the crank 21 which extends preferably in a general direction away from the pivot of the arm 18 and terminates in the cam-follower 20. When the arm 18 is at the extremity of its movement the ends of the 75 cam-slot 19 are preferably extended away from the axis of the looper-spindle 22, as illustrated in Fig. 2. Starting at the position shown in Fig. 2, as the shaft 14 rotates, the arm 18 is moved to the right and first 80 imparts a relatively rapid turning movement to the looper-spindle 22. This movement is slowed up as the cam-follower 20 rounds the bend at substantially the central portion of the cam-slot 19 and enters the 85 lower end-portion of said cam-slot which is nearly straight and substantially tangent to its circular path of movement about the pivot of the arm 18. Therefore, when the cam-follower 20 reaches this portion of the 90 cam-slot 19, the looper-spindle will pause. In the reverse movement of the arm 18 the initial pause of the looper-spindle 22 will be followed by an accelerated motion as the cam-follower 20 rounds the bend in the cam-slot and enters the upper end-portion of said 95 cam-slot, as will be obvious to those skilled in the art. Thus, the form of the cam slot 19 is such that there are produced the pause and accelerated motion required for the production of a perfect double-loop stitch with an oscillating looper the radius of oscillation of which is limited on account of the restriction of the space available to the clear cross sectional area of the tubular post in 105 which the looper is housed.

Provision is made for adjustment of the effective length of the pitman 17 as it will be apparent that by loosening the lock-nuts 17''' the rod 17 may be turned to either 110

lengthen or shorten the pitman 17 in a well known manner, after which the lock-nuts may be retightened.

The presser bar 12 reciprocates in a guide 5 carried by a bracket 23 pivoted at its upper end and forming a pendulum support for the presser bar, oscillatory movements around a horizontal axis being imparted to the bracket.

10 The presser foot 24, 25 is divided or split in the direction of the length of said foot. In order that the halves may be readily adjusted relatively to one another so as to provide for the unequal thickness of the 15 work due to the overlapping of the edges to be united, the forward half, that is to say the accessible half 24, of the presser foot is fitted so as to be slidable vertically relatively to the rearward half 25 to which it is 20 connected by a screw 26 passing through a slot in said forward half and threaded into the presser bar 12. The forward half 24 of the presser has an upward extension 27 having an aperture at its upper extremity to 25 receive an eccentric 28 mounted on a pin 29 projecting from a block or collar fixed to the presser bar; fixed to said eccentric 28 is a disk 31 having perforations, serrations or the like on its forward face adapted to 30 coöperate with an index finger 32 fitted to the pin 29. It will be understood that the operator by rotating the disk 31 and therewith the eccentric 28 will adjust the forward half 24 of the presser foot, the index 35 finger 32 engaging one of the perforations or the like and serving to lock the disk 31 in any desired position of adjustment.

The presser-foot mechanism described herein is not claimed since it forms the subject-matter of my divisional application Serial No. 169,885, filed May 18, 1917.

40 While I have shown and described what I consider to be the preferred form of the invention, it is to be understood that the form 45 and arrangement of the essential elements are susceptible of modification within the scope of the invention.

It is to be understood that all novel features of the present improvement as shown 50 and described herein are of my invention.

I claim:—

1. In a sewing machine, in combination, a rotating shaft, a pivoted arm deriving oscillatory movements from said shaft, said arm being formed with a curved cam-slot, a looper-spindle having its longitudinal axis disposed substantially in parallelism with the axis of oscillation of said arm, a crank on said spindle, and a follower carried by 55 said crank and entering said cam-slot, said cam-slot having an operative portion extending in a direction substantially tangent to the circular path of movement of said portion as determined by the oscillation of 60 said arm.

2. In a sewing machine, in combination, a rotating shaft, an eccentrically mounted member carried thereby, a pivoted arm having a cam-track, a link connecting said arm to said eccentrically mounted member, and a looper-supporting spindle having its longitudinal axis disposed substantially in parallelism with the axis of oscillation of said pivoted arm and provided with a crank-arm, 70 said crank-arm having a cam-follower engaging said cam-track, said cam-track having a pause-producing operative portion substantially tangent to the path of movement of said portion as determined by the oscillation of said arm and also having an operative portion extending in a direction 75 at an angle to said pause-producing portion.

3. In a sewing machine, in combination, a rotating shaft, a pivoted arm deriving oscillatory movements from said shaft, said arm being formed with a curved cam-track which is convexed toward the pivot of said arm, a looper-spindle having its longitudinal axis disposed substantially in parallelism with the axis of oscillation of said arm, and a 80 crank on said looper-spindle having a cam-follower engaging said cam-track.

4. In a sewing machine, in combination, a rotating shaft, a pivoted looper-driving arm deriving oscillatory movements from said 95 shaft, a looper-spindle, said arm being formed with a curved cam-track convexed toward the pivot of said arm, said pivot being so positioned that substantially the central portion of said cam-track is adapted to 100 be intersected by the axis of said looper-spindle when vibrated to-and-fro across said axis, and a crank on said looper-spindle extending in a general direction away from the pivot of said looper driving arm and 105 having a cam-follower in engagement with said cam-track.

5. In a sewing machine, in combination, a rotating shaft, a looper driving arm deriving oscillatory movements from said shaft, 110 a looper-spindle, said arm being formed with a curved cam-track whose extremities are extended substantially directly away from the axis of said looper-spindle when said arm is at one of its extreme positions, and a crank on said looper-spindle having a cam-follower engaging said cam-track.

6. In a sewing machine, in combination, a rotating shaft, a looper-driving arm deriving oscillatory movements from said shaft, 120 a looper-spindle, said arm being formed with a curved cam-track whose extremities are extended substantially directly away from the axis of said looper-spindle when said arm is at one of its extreme positions, 125 and a crank on said looper-spindle having a cam-follower engaging said cam-track, said crank extending in a general direction away from the pivot of said looper driving arm.

7. A sewing machine having, in combina- 130

tion, a frame including an upright work-supporting post, a looper-spindle extending lengthwise of said post, a rotating shaft, a pivoted arm deriving oscillatory movements 5 from said shaft, said arm being formed with a curved cam-slot, a crank on said spindle, and a follower carried by said crank and entering said cam-slot, said cam-slot having an operative portion extending in a direction substantially tangent to the circular 10

path of movement of said portion as determined by the oscillation of said arm.

In testimony whereof I have signed my name to this specification in the presence of two subscribing witnesses.

JAMES HEGGIE.
